INCANDESCENT ELECTRIC LAMP

William T. Cowhig, Rugby, England, assignor to
 General Electric Company, a corporation of
 New York

Application June 20, 1938, Serial No. 214,824
 In Great Britain July 13, 1937

4 Claims. (Cl. 176—29)

The present invention relates to incandescent electric lamps and more particularly to such lamps in which a relatively short coiled filament of a refractory metal such as tungsten is mounted 5 within and sealed into an envelope consisting of a tube of quartz or other like strong, heat resisting transparent or translucent vitreous material so as to lie axially within the tube.

One of the difficulties which arise when a tungsten filament is mounted in a small quartz or glass envelope has been that the filament sags during 10 operation and approaches the wall of the envelope. It is not convenient to introduce a support along the length of the lamp owing to the small diameter of the envelope, so that it is 15 desirable to eliminate this sag by drawing the filament taut after it has been flash aged during the lamp exhausting operation.

One object of my invention is to provide a 20 method of mounting the filament of an electric incandescent lamp so that it may be easily drawn taut without weakening the lamp envelope.

According to the invention, the sealing of the 25 leading-in wires into the drawn-down ends or neck portions of the tubular envelope is effected at points somewhat spaced from the body of the envelope, and after the envelope has been sealed-off the portion of one or both of the drawn-down ends of the envelope, adjacent the body thereof, 30 is heated to soften it, and the leading-in wires are drawn apart to taunt the filament while the said portion or portions is or are softened.

Further objects and advantages of our invention 35 will appear from the following description of a species thereof, taken in connection with the accompanying drawing which is a side elevation of an electric incandescent lamp illustrating the method of mounting the filament therein according to the invention.

Referring to the drawing, there is shown a 40 typical double-ended lamp comprising a filament 1 mounted within a small tubular envelope 2 preferably of quartz or other high heat-resistant glass. The filament 1 is disposed substantially 45 axially of the tubular envelope 2 which is of relatively small internal diameter. Opposite ends of the filament are connected to current supply or leading-in wires sealed into reduced end or neck 50 portions 2' of the lamp envelope 2, each of said wires comprising a length of molybdenum wire 3 secured to the filament 1, a strip 4 of molybdenum foil attached to the wire 3, and a section of molybdenum strip 5 secured to the foil 4. The 55 actual seal between the quartz lamp envelope 2

and the current supply wires is made at the foil 4.

The filament assembly is sealed into the quartz or glass envelope 2 in the usual way, using the above-described molybdenum strip seal. In the usual method of making these lamps, the seals are at a relatively short distance, such as 1 or 2 mm., from the body of the lamp envelope 2. According to my invention, however, the seal is 10 made at a considerably greater distance from the body of the lamp envelope, preferably at a distance of about $\frac{1}{2}$ to 1 cm. therefrom, as shown in the drawing. The lamp envelope is then exhausted through the exhaust tube 6 after which the filament is then burned or flash aged in the customary manner until recrystallization processes, etc., are complete. The exhaust tube 6 having been tipped, the envelope neck portion A 15 immediately adjacent the body of the envelope 2 is then softened and the filament 1 drawn taut by a pulling-out or stretching operation. One or both of the envelope neck portions A between the body of the envelope and the current supply wire seal may be softened to permit this drawing-out 20 or stretching of the filament.

What I claim as new and desire to secure by Letters Patent of the United States is:

1. The method of mounting a longitudinally extending coiled filament, having leading-in wires connected to its opposite ends, within a tubular glass envelope having reduced end portions, which comprises sealing said leading-in wires into said reduced end portions, at least one of said leading-in wires being sealed at a point considerably removed from the body of said envelope to thereby provide an extended neck portion between the body of said envelope and the said seal, softening said extended neck portion of said envelope, and then drawing the said filament taut while the said extended neck portion is still plastic.

2. The method of mounting a longitudinally extending coiled filament, having leading-in wires connected to its opposite ends, within a tubular glass envelope having reduced end portions, which comprises sealing said leading-in wires into said reduced end portions at points considerably removed from the body of said envelope to thereby provide extended neck portions between the body of said envelope and the said seals, softening at least one of said extended neck portions, and then drawing the said filament taut while the said extended neck portion is still plastic.

3. The method of mounting a longitudinally

extending coiled filament, having leading-in wires connected to its opposite ends, within a tubular glass envelope having reduced end portions, which comprises sealing said leading-in wires into said reduced end portions, at least one 5 of said leading-in wires being sealed at a point considerably removed from the body of said envelope to thereby provide an extended neck portion between the body of said envelope and the 10 said seal, exhausting said envelope and operating said seal, exhausting said filament until recrystallization thereof is complete, softening said extended neck portion of said envelope, and then drawing the said filament taut while the said extended neck portion 15 is still plastic.

4. The method of mounting a longitudinally

extending coiled filament, having leading-in wires connected to its opposite ends, within a tubular glass envelope having reduced end portions, which comprises sealing said leading-in wires into said reduced end portions at points 5 considerably removed from the body of said envelope to thereby provide extended neck portions between the body of said envelope and the said seals, exhausting said envelope and operating said filament until recrystallization thereof is complete, softening at least one of said extended neck portions, and then drawing the said filament taut while the said extended neck portion 10 is still plastic.
